A. HARDONCOURT, JR.
WALL CONSTRUCTION.
APPLICATION FILED JULY 16, 1915.

1,299,180.

Patented Apr. 1, 1919.

Inventor:

Arthur Hardoncourt, Jr.

by *Geo. M. Maxwell,*
Attorney.

UNITED STATES PATENT OFFICE.

ARTHUR HARDONCOURT, JR., OF BROOKLYN, NEW YORK.

WALL CONSTRUCTION.

1,299,180.

Specification of Letters Patent.

Patented Apr. 1, 1919.

Application filed July 16, 1915. Serial No. 40,251.

To all whom it may concern:

Be it known that I, ARTHUR HARDONCOURT, Jr., a subject of the Emperor of Austria-Hungary, and resident of New York, 5 borough of Brooklyn, in the county of Kings and State of New York, have invented an Improvement in Wall Constructions, of which the following description, in connection with the accompanying drawings, is a 10 10 specification, like letters on the drawings representing like parts.

My present invention is a wall construction for channel brick, particularly intended to enable a channel brick type of wall to be 15 laid up at corners, and is directed in part to certain features of the invention illustrated in my prior Patent No. 1,068,338 of July 22, 1913, but which could not be claimed there-in, and of my copending application, Serial No. 40,250, filed July 16, 1915.

In constructing a hollow wall wherein the air spaces or voids are formed horizontally with an open continuous space throughout the length of a course, it is not feasible to 25 use open ended brick at corners as an open end would be exposed, and prior to my invention no method of bonding such channel brick and common brick headers was known or practised. However, I have discovered a 30 means of bonding and closing the horizontal ends of my channel brick with an overlapping header, whereby such brick may be partly in the pier of each corner, thus integrally carrying the channel brick into the 35 corner piers, and preferably having the side of one brick partially close the voids of another, and requiring only a small filler or header to close the open end of the channel.

This feature is of especial importance in 40 that type of channel brick having raised projections on the upper side which serve to interlock with depending webs of the next superimposed row, such projections, of course, being at an angle to each other at 45 each corner. In a square corner such projections will be at right angles and would not permit being crossed and the corner block being on the same mortar joint as the rest of the wall and of the corner pier construction. At obtuse angle corners, such 50 projections will be at a similar angle to that of the corner, as will readily be understood.

Other important features, details of construction, and advantages will be hereinafter 55 more fully pointed out and claimed.

Referring to the drawings illustrating preferred constructions and modifications of corners,

Figure 1 is a perspective view of a corner wall illustrating the invention utilizing a 60 channel brick of the type of that shown in said prior Patent No. 1,068,338;

Fig. 2 being a similar perspective view illustrating the manner in which the small header brick are used to partially close the 65 open channels in adjacent brick;

Fig. 3 is a perspective view of single channel brick also of the type shown in my said patent;

Fig. 4 is a perspective of the type of channel brick illustrated in my pending application, Serial No. 40,250, filed July 16, 1915;

Fig. 5 is a further view of channel brick of the single channel type illustrated in said pending application.

While I have herein illustrated various modifications of corner construction wherein the channel brick of the U-shaped or double-U-shaped type are shown, it will be understood that my present invention of corner 80 construction is not necessarily limited to these particular types of channel brick but is useful and important in any hollow wall construction wherein U-shaped brick of the type more fully described in my said patent 85 and application are built into a wall and wherein such channel brick are carried partly into the corner piers or corner edges, thus utilizing the hollow wall construction right into the corners of the wall and obtaining all 90 benefits and advantages in said corners of the horizontal air space construction, if desired.

The foundation is designated by the reference character 1 on which a lower mortar 95 course 2 is laid, the type of channel brick illustrated in Figs. 1 and 2 being built thereon as shown at 3 directly into a part of the corner. Each endmost channel brick having the series of projections 4 and 5 on the upper part, and the depending webs 6 on the lower part, may have said uppermost projections readily knocked off by the hammer or the trowel of the workman, to provide a flat surface 7 sufficient to receive the depending webs of the right angled channel brick of the next course. As shown in Fig. 1, the channel bricks 8 have the uppermost projections partially removed to overlap the open ends of the channel brick at right an- 110

gles thereto, thus partially closing said voids and leaving the header block 9 to complete said closings. As illustrated in Fig. 2 these header blocks 9 will be bonded at right angles to each other, each block closing a part of the channel in the right hand wing of the wall left partly open by the overlapping of the endmost channel brick 8, and closing the entire end of such overlapping channel brick. The header 9 may be of hollow construction as illustrated in the drawings, or may be of solid brick, in either case the removal of part of the raised portions or projections 4 and 5 enable the adjacent depending webs 6 of one brick to be bonded on the flat surface 7, and the header 9 to also be fitted thereon. As the channel brick of my invention are preferably of standard brick size in height, the appearance of the corner wall thus constructed is identical with that of a solid brick formation and thus carries out to the greatest extent the hollow construction into all corners and edges.

In the type of channel brick illustrated in Fig. 3, a similar header 9 is shown, the channel brick 12 therein shown, being formed with one pair of depending webs 13 and 14 and a single pair of raised projections 15 and 16, which latter are partly broken off to leave the flat space 17 upon which the overlapping adjacent brick and header may be fitted.

In the modification illustrated in Fig. 4, a similar header 9 is shown for the corners, wherein the channel brick 18 are formed with a plurality of raised projections 19 and 20 and depending webs 23. The raised portions 19 and 20 are cut off, leaving the flat top part 21 and the relatively thin tie portions 22. As there is no vertical strain on these thin portions 22 they are sufficient to hold the remaining half portion of each brick 18, being also sufficiently solid to enable a part of the raised portions 19 and 20 to be thus removed.

Fig. 5 shows a still further modification of the type of channel brick illustrated in Fig. 4, and shown in my said co-pending application, wherein similar headers 9 are employed and each channel brick 25 has a single raised portion 26, partly cut away to leave the projecting part 27 of the top of each brick, where it juts into the corner or pier construction, smooth, to permit the depending webs 28 of the next overlapping brick to be positioned.

It will also be noted that the removal of the raised portions on the top of the channel brick, acts as a guide and interlocking for the depending side web of the adjacent overlapping channel brick. In Fig. 1 for example, the endmost brick 8 on the left wing with its depending web 6 interlocking upon the projections of the lower full channel brick 3, also interlocks with the abutting

ends of the raised projections 5 on the right hand lower brick 8, being firmly secured therein by the bonding material 29, and constituting a gage or stop for the next or topmost full channel brick 3 on the right wing. This greatly facilitates corner building and the same advantage accrues in the construction shown by the various modifications of the other figures of the drawing.

While I have only illustrated the corner construction in right angled or squared corners, it will readily be understood that the projecting portions of such channel brick may be cut at an angle corresponding with that of the two wings forming the corner. The channel brick can thus be carried directly into the corner construction, if desired be closed and tied by a single header. It will be seen that I have enabled channel brick of the type described, with overlapping and interlocking projections adapted to so overlap in the wall, nevertheless be carried into a corner where such overlapping and interlocking projections could not normally be built uniformly level with the course, as the interlocking means would prevent same. Although I prefer to remove the topmost ribs or projections as illustrated in the drawings, it is also within the scope of certain of the appended claims to remove parts of the depending interlocking means, i. e. the webs which could readily be cut by a trowel to span the space of a small rib without injury to the load-carrying capacity of the corner. Such an arrangement would obviously be an equivalent construction to the preferred arrangement shown in the drawings. The vital point of the invention is that channel brick are so combined at a corner where ordinarily the open ends would be exposed, to be bonded with a header having plain sides and ends, such header partly overlapping and bonding the channel brick in adjacent rows or courses and simultaneously closing the openings. By

having my channel brick of substantially standard brick size in height, an ordinary brick or brick pier can be used and a brick of each course extended into overlapping bonding and closing relation with the adjacent channel brick course. Preferably, I extend the channel brick courses directly into the corner, but it will be readily appreciated that a solid brick corner pier with the headers extended therefrom into the channel brick course could be employed, such channel brick receiving and bonding same on the same plane of the mortar joint of both pier and channel brick wall. While this is specially useful at corners as explained, such bonding between channel brick and common brick may be at a solid brick pier in a channel brick wall, at windows, doors, etc.

Having described my invention, what I

claim as new and desire to secure by Letters Patent is:

1. Hollow wall construction, comprising channel brick adapted to be laid horizontally, forming horizontal open-ended air spaces, said brick having raised projections and depending webs adapted to interlock with adjacent courses, means for the depending webs of one course to overlap the adjacent lower course at corners while having said corner course level, in combination with a header of standard brick size to close the open-ended air spaces of each abutting channel brick course in a corner, the end channel brick of one course partially overlapping and closing the open end of the adjacent course of brick, and a header completing the closing of said partly closed course and entirely closing the open end of the first-mentioned channel brick.
2. Wall construction of channel brick, comprising channel brick of the kind described, having a part of each brick extending across and overlapping the adjacent channel brick constituting the wall pier at a corner, with obstructing projections cut off from that part of the brick which extends into the pier, and a header to close the open ends of abutting channel bricks.
3. Wall construction comprising two angularly disposed walls formed of channel brick laid horizontally forming a corner at

which the alternate channel brick extend partially across and overlap adjacent angularly disposed channel brick and a header 35 filling the space formed between the ends of adjacent channel brick and closing the openings in such ends.

4. Hollow wall construction consisting in channel brick interlocked with standard 40 sized brick, said channel brick comprising a horizontal body portion having depending webs inclosing a horizontal air space on one side of said body portion which webs are of a substantially standard brick size in outer 45 exposed area, raised portions on the opposite sides of the body portion, so that the vertical height of the raised portions and depending webs are greater than the height of said standard sized brick with which the 50 channel brick interlocks, said channel brick having a part of the raised portion removed at corners, whereby the depending webs and standard sized brick are laid flush in alignment at corners, piers, and the like, and 55 said horizontal air spaces are closed.

In testimony whereof, I have signed my name to this specification, in the presence of two witnesses.

ARTHUR HARDONCOURT, JR.
